UNITED STATES PATENT OFFICE.

DANIEL TIBBALS, OF ST. LOUIS, MISSOURI, ASSIGNOR TO THOBAL ELECTRIC COMPANY, OF ST. LOUIS, MISSOURI, A CORPORATION OF MISSOURI.

ELECTRIC MASSAGE-ROLL.

1,059,090.

Specification of Letters Patent.

Patented Apr. 15, 1913.

Application filed September 24, 1909, Serial No. 519,339. Renewed June 21, 1912. Serial No. 705,102.

To all whom it may concern:

Be it known that I, DANIEL TIBBALS, a citizen of the United States, residing at the city of St. Louis, State of Missouri, have 5 invented certain new and useful Improvements in Electric Massage-Rolls, of which the following is a specification, reference being had to the accompanying drawings, forming a part hereof, in which—

10 Figure 1 is a longitudinal sectional view, partly in elevation, of my new electric massage roll or instrument; Fig. 2 is a fragmentary elevational view thereof, partly broken away; Fig. 3 is a sectional view taken approximately on the lines 3—3 of Figs. 1 and 2; Fig. 4 is a plan view of the under side or face of the closure for the upper end of the shell or casing forming the handle of my new instrument and which closure also directly supports the massage roll; Fig. 5 is a vertical sectional view through said closure taken approximately on the line 5—5, Fig. 4; Fig. 6 is an elevational view of the induction coils and their supporting - frame 25 used in my new instrument, showing also the armature therefor and the several leads from the secondary winding thereof, whereby the intensity of the induced current supplied to the electrodes may be regulated or 30 varied; Fig. 7 is a detail sectional view taken approximately on the line 7—7 of Fig. 6; and Fig. 8 is a diagrammatic view of the primary and secondary electric circuits through my new massage instrument or roll.

35 This invention relates to certain new and useful improvements in electric massage instruments or rolls, the objects of my invention being to provide an instrument of the kind stated which is comparatively simple 40 in construction, which may be manufactured and supplied or furnished users or consumers at small cost, in which the intensity of the current or electric sensation applied to the user may be readily and easily regulated or varied, in which the battery energy 45 is conserved and the life of the battery correspondingly lengthened, in which the electrical sensation or current applied to the user is smooth, even, and steady and approximately 50 free from shocks, in which the primary circuit, and therewith also the secondary circuit, may be readily opened and closed at will, by which a comparatively large, heavy, or intensified current may be furnished with 55 a small battery, and in which the massage

instrument is adapted to distribute the massage lotion evenly and uniformly over the portions of the body being treated, and to improve generally upon instruments of the kind described.

With these objects in view, my invention resides in certain novel features of construction, arrangement, and combination of parts, all as hereinafter fully described and afterward pointed out in the claims.

Referring by numerals to the accompanying drawings, 1 indicates a preferably open-ended metallic or electrical conducting cylindrical shell or casing, which is adapted to provide the handle of my new massage instrument and which also forms part of the primary circuit therethrough, as hereinafter more fully appearing.

Within the lower portion of shell 1, as shown particularly in Fig. 1, is removably positioned a suitable electric battery or cell 2 preferably cylindrical in shape and of such size relatively to the interior diameter of shell 1 so as to fit snugly therein, battery 2 being preferably of that type wherein the outer wall thereof, as at 2^a, forms one element of the battery and the head of the other element, as at 2^b, projects upwardly slightly beyond the top thereof. Battery 2 is preferably insulated at its sides from the sides of shell 1 by means of suitable insulation material 3 interposed therebetween and is removably held in position in shell 1 by means of a suitable metallic cap-piece 4 threaded on, and adapted to close, the lower end of shell 1, a suitable coiled spring or the like 5 preferably electrically secured to cap 4 and interposed therebetween and the lower end of battery 2 being adapted not only to normally contact with and thereby form an electrical connection between battery element or contact 2^a and cap 4 and shell 1, but also to normally maintain battery element or contact 2^b in constant contact with a suitable metallic plate or contact 6^a arranged on the under face of, and secured in position by means of a suitable metallic screw 6 extending upwardly through the base 7 of a member A removably arranged in casing 1 and bodily rotarily movable about the longitudinal axis thereof above battery 2, as shown particularly in Fig. 1. This member A comprises said base 7, which is preferably a disk of any suitable insulation material, a head 8, which is

80
85
90
95
100
105
110

likewise preferably a disk of any suitable insulation material, and a vertically-disposed substantially U-shaped metallic frame 9 interposed between said base 7 and head 8, 5 said frame 9 being integrally provided with upper and lower flanged portions 9^a and 9^b, respectively, adapted to receive and electrically engage or contact with, respectively, said screw or contact 6 and a screw or other 10 suitable contact 10 extending upwardly through said head 8 and whereby also said frame 9 is securely held in position between said base 7 and head 8. Mounted on and carried by said frame 9, as shown particularly 15 in Figs. 1 and 6, are induction coils 11-11'. These coils 11-11' are preferably supported on frame 9 by means of suitable metallic screws 12-12 passed through one flange, as, for instance, flange *a*, of frame 9 into the cores thereof, as shown particularly 20 in Fig. 6, the said cores, screws 12-12, and the portion of flange *a* of frame 9 between said screws thereby forming substantially a horse-shoe-shaped core or magnet adapted 25 to be magnetized and having its opposite leg-portions closely adjacent, for purposes hereinafter appearing.

Arranged preferably on the core of lower coil 11, and insulated therefrom and from 30 flange *a* of frame 9 and coil 11 by suitable insulation blocks 13 and 14, as shown particularly in Fig. 6, is the leg 15' of a small substantially U-shaped metallic bracket 15 having its body-portion lying between and 35 spaced from coil 11 and the body-portion of frame 9 and its said leg 15' and opposite leg 15" presented forwardly as shown, see particularly Figs. 1 and 6.

The primary winding of coils 11 and 11', 40 which may be of any suitable length, is preferably in series, one end, as at *c*, thereof being grounded upon, or electrically connected to, said insulated leg 15' of bracket 15, as shown particularly in Fig. 7, 45 and the opposite end, as at *d*, passing through a suitable opening in said flange *a* of frame 9 and being electrically connected to a suitable extended arc-shaped contact terminal 16 arranged on the outer face of 50 head-disk 8, see particularly Figs. 1 and 3. Secured, as shown, and electrically connected to the opposite flange, or to flange *b*, of frame 9, is an elongated spring-member 55 18 angularly bent, as shown, to normally loosely lie against and swingably contact at its lower or free end with said leg 15" of bracket 15; and arranged on the inner face of, and carried by, the free end of spring-member 18, as shown, is an armature member 19 adapted to coöperate with and be alternately attracted by and drawn out of 60 engagement with the legs of said magnet, as will be well understood. The secondary winding of said coils is provided with, or 65 divided by, a plurality of leads electrically

connected, respectively, to suitable spaced apart or separated contact terminals *j*, *i*, *h*, *g*, *f*, and *e*, arranged preferably in the form of an arc on the outer face of head-disk 8 and directly opposite said contact terminal 16, as shown particularly in Figs. 3 and 6, 70 so that the intensity of the induced current supplied to the electrodes of the instrument may be varied or regulated, as hereinafter more fully appearing, said winding with 75 its said leads being formed or wound as follows: The wire of the secondary winding, which is, as is usual, very fine, is at one end first suitably connected preferably to the end *d* of the primary winding, then given 80 a predetermined number of windings or turns on the primary winding, then led to, and electrically connected with, first contact *j*, then again given a predetermined number of windings or turns on the primary 85 winding, then led to, and electrically connected with, second contact *i*, then again given a predetermined number of windings or turns on the primary winding, then led to, and electrically connected with, contact *h*, 90 and so on throughout said series of separated contacts, there being preferably approximately on the coils here shown forty-five feet of wire of the secondary winding wound 95 on the primary winding between the several respective contacts of said series and the secondary wire being finally electrically connected at its other end to the last contact *e*. Secured, by means of suitable screws or other fastening devices 20, in, and adapted 100 to close, the upper end of shell 1, is a preferably rounded, somewhat coneshaped block of suitable insulation material 21 preferably provided on its under face with an integral depending ring-shaped portion 22.

23 indicates a suitable metallic roller which is adapted to provide one of the electrodes of my new instrument. This roller 105 23, which is preferably hollow and provided on its periphery with a plurality of circular or cup-shaped recesses or depressions 24, is suitably supported by, and journaled in and between the outer ends of, the outwardly-extending legs 25-25 of a substantially U-shaped metallic frame 26 mounted 110 on said insulation block 21 and held in position thereon by, and electrically contacting with, a suitable metallic through-bolt 27 extending longitudinally through said block 21 with its lower end within said ring-portion 22 and threaded to receive a securing-nut 28.

Suitably secured at or adjacent one end, as by screws 29, on, and preferably adjacent the outer edge of, the under face of insulation member or closure 21, are suitable substantially arc-shaped contact members 30 and 31 adapted, respectively, to coöperate and electrically engage on the rotary movement of member A with said contact 16 130

and said series of separated contacts *j*, *i*, *h*, *g*, *f*, and *e* arranged on disk or head 8, said contact members 30 and 31 being each at its free end gradually bent or curved downwardly and then at its end bent upwardly, so as to provide curved portions, as at 30' and 31', respectively, adapted to ride easily and smoothly over and electrically engage with said contacts on disk or head 8. Suitably secured on the under face of said insulation block 21 is a short metallic strip 32 adapted to electrically connect said contact member 31 with said through-bolt 27 and its carried roller or electrode 23; and also arranged on the under face of block 21 and electrically connected to contact-member 30 is a short metallic strip 33 extending outwardly to the edge of block 21, where it is bent upwardly, as at 33', and thereby adapted to electrically contact with, and complete the primary circuit to, shell 1. At proper place relatively to head-disk 8, shell 1 is provided with a circumferential slot, as at 34, and arranged on shell 1, so as to cover said slot 31, is a ring 35 held in position by means of a preferably knob-headed screw 36 threaded into said disk 8 and which screw 36 serves also as operating means for rotarily moving said member A in shell 1 to move said contact members 30 and 31 into electrical engagement with the said contacts on head 8 and thereby complete the primary circuit and throw the electrode or roller 21 into the secondary circuit. When operating-screw 36 is at the left-hand end of slot 34 or at zero or normal position, contact-members 16 and 30, as well as also said contact-member 31 and said series of separated contacts, are out of contact or electrical engagement and the primary circuit is open. On member A being rotarily moved to the right, contact-members 16 and 30 are brought into engagement and the primary circuit is then closed and completed from battery element or contact 2^b, through plate 6^a screw 6, frame 9 and its flange 7, spring member 18, bracket 15, primary-winding of coils 11 and 11', contact-member 16, strip 33, casing or shell 1, cap 4, and coiled spring 5 to other battery element or contact 2^a. Normally, as before stated, the free end of spring 18 is in electrical engagement with bracket 15; as soon, however, as the current from battery 2 begins to circulate in said primary winding of coils 11 and 11' and around the cores thereof, said cores forming said magnet become magnetized and thereby said armature 19 is alternately attracted and, on the intermittent breaking of the current by said spring 18 being so moved out of contact with bracket 15, drawn out of electrical engagement therewith by spring 18 returning to normal position. These said actions take place in rapid succession and con-

stantly produce a change in the lines of force passing through said magnet or cores, thereby inducing a current in the secondary winding, the current from which will flow through one of said separated contacts *j*, *i*, *h*, *g*, *f*, or *e*, depending upon the rotated position of member A, through contact-member 31, strip 32, bolt 27, and frame 26, to electrode or roller 23, the intensity of such induced current being readily regulated or varied by bodily rotating member A and thereby bringing contact member 31 into electrical engagement with one of said contacts of said series, as may be desired, the induced current flowing through contact *j* being of least intensity and the induced current flowing through contact *e* being of greatest intensity. The shell or casing 1 may be provided adjacent slot 34 with a series of numbers, as shown, to indicate the engagement of contact member 31 with a particular contact of said series and thereby enable the operator to visually gage the strength or intensity of the current supplied to the electrode or roller 23. By arranging said coils as shown with their cores closely adjacent, the pulsations of the primary circuit are exceedingly rapid with the armature 19 moving or swinging back and forth likewise exceedingly rapidly and shocks to the user are consequently eliminated, and by my construction as described I am enabled to develop a comparatively large or heavy induced current in the secondary winding with a small battery and, at the same time, conserve the energy, and thereby lengthen the life, of the battery. In operation or use, my new instrument may be personally employed, and the massage roller 23 applied to or rolled upon the portion of the body to be treated, by the patient himself, or the treatment may be applied upon the patient by an operator or the like. In the former case, shell 1 is grasped in the hand of the patient and the massage roller or electrode 23 personally applied to or rolled upon the portion of the body to be treated, the current flowing from electrode or roller 23 through the body of the patient back to shell 1 and battery 2. In the latter case, an electrode E comprising a suitable preferably wooden or other insulation handle 37 provided at one end with a metallic plate 38 having secured thereto a sponge or the like 39 and electrically connected, as shown, to cap 4 by means of a wire or the like 40, is grasped by handle 37 in the hand of the patient or operator, wet sponge 39 applied to a portion of the body of the patient and roller or electrode 23 then by the operator applied to or rolled upon the portion of the body of the patient to be treated, the current, as will be clear, flowing through the body of the patient. By means of said indentations or

130

depressions 24, massage roller 23 is especially and peculiarly well adapted to carry and evenly and uniformly distribute and apply the massage fluid or lotion over the 5 portion of the body being treated.

5 I am aware that minor changes in the construction, arrangement, and combination of the several parts of my new massage instrument may be made and substituted for those 10 herein shown and described without departing from the nature and spirit of my invention.

What I claim is:—

1. A massage instrument comprising a 15 conducting handle, a conducting massage implement carried by said handle, an induction coil in the casing having an extended contact terminal at one end for the primary winding and a divided secondary winding 20 with a series of separated terminals at the same end of the induction coil as the extended primary contact, a source of intermittent current in the handle for the primary winding of the induction coil, conducting 25 brushes in the casing in operative relation to the terminals of the secondary winding of the induction coil and the extended primary terminal contact, and means accessible from the exterior of the casing 30 for causing a relative movement of the brushes and the contacts carried by the induction coil.

2. A massage instrument comprising a 35 conducting handle, a conducting massage implement carried by said handle, an induction coil in the casing movable about the longitudinal axis of the casing and provided with an extended contact terminal at one end for the primary winding of the 40 coil, said induction coil also having a divided secondary winding with a series of separated contact terminals at the same end of the coil as the extended primary contact, a source of intermittent current in the 45 handle for the primary winding of the induction coil, fixed conducting brushes in the casing in operative relation to the terminals of the secondary winding of the induction coils and the extended primary contact terminal, and means accessible from the exterior of the casing for causing a rotative movement of the induction coil to bring the brushes into engagement with said extended primary contact and with chosen 50 ones of the secondary contact terminals.

3. A massage instrument comprising a 55 handle in the form of a conducting casing, an insulating closure for one end of the casing, a massage instrument carried by the insulating closure, contact brushes carried by the insulating closure, one of said brushes being connected with the massage implement and the other with the casing, an induction coil within the casing and provided 60 at one end with contacts adapted to engage

the respective brushes carried by the closure, a rheotome carried by the induction coil, a battery within the casing and means accessible from the exterior of the casing for rotating the induction coil about its longitudinal axis to bring the contact terminals carried by the induction coil into engagement with the brushes carried by the insulating closure. 70

4. In a massage instrument, a conducting 75 handle, a conducting massage implement carried by, and insulated from, said handle, an induction coil in the handle rotarily movable about the longitudinal axis thereof, said coil having an extended contact terminal at one end for the primary winding thereof and a divided secondary winding with a series of separated contact terminals at the same end thereof as said extended primary contact, a source of intermittent current in the handle for the primary winding of said coil, fixed conducting contacts in the casing in operative relation to the said separated terminals of said secondary winding of said coil and to said extended primary contact terminal, one of said fixed contacts being adapted, on the engagement therewith of said extended primary contact, to close the primary circuit through said handle and the other of said fixed contacts being adapted, on the engagement therewith of one of said separated contacts, to throw said massage implement in the secondary circuit, and means accessible from the exterior of the casing for causing a rotative 90 movement of said coil to bring its said contacts into engagement with said respective fixed contact terminals; substantially as described. 95

5. In a massage instrument, a conducting 100 handle, a conducting massage implement carried by, and insulated from, said handle, an induction coil in the handle rotarily movable about the longitudinal axis thereof, said coil having an extended contact terminal 105 at one end for the primary winding thereof and a divided secondary winding with a series of separated contact terminals at the same end thereof as said extended primary contact, a source of intermittent current in the handle for the primary winding of said coil, fixed conducting contacts in the casing in operative relation to said extended primary contact and to said series of separated contacts, one of said fixed contacts being in 110 electrical connection with said casing and the other of said fixed contacts being in electrical connection with said massage implement, and means accessible from the exterior of said casing for causing a rotative movement of said coil to bring its said extended primary contact and one of said contacts of said series into electrical engagement with said respective fixed contacts and thereby close the primary circuit through 115 120 125 130

said casing and throw said massage implement in the secondary circuit; substantially as described.

6. In a massage instrument, a handle in the form of a conducting casing, an induction coil in said casing rotarily movable about the longitudinal axis thereof, said coil having an extended contact terminal at one end for the primary winding thereof and a divided secondary winding with a series of separated contact terminals at the same end thereof as said extended primary contact, a source of intermittent current in said casing for the primary winding of said coil, a closure of insulation material fitting in one end of said casing, a massage implement carried by said closure, fixed conducting contacts on said closure in operative relation to said series of separated terminals of said secondary winding of said coil and to said extended primary contact terminal, one of said fixed contacts being in electrical connection with said casing and the other of said fixed contacts being in electrical connection with said massage implement, and means accessible from the exterior of said casing for causing a rotative movement of said coil to bring its said extended primary contact and one of said secondary contact terminals into electrical engagement with said respective fixed contacts and thereby close the primary circuit through said handle and throw said massage implement in the secondary circuit; substantially as described.

7. In a massage instrument, a handle in the form of a metallic casing, a member rotarily movable in said casing about the longitudinal axis thereof, an induction coil with its armature carried by and movable with said member and having a divided secondary winding, a battery in said casing normally in electrical connection with the primary winding of said coil and its said armature and adapted therewith to provide a source of intermittent current for the primary winding of said coil, an extended contact terminal carried by said member for the primary winding of said coil, a series of separated contact terminals for said divided secondary winding of said coil carried by said member at the same end thereof as said extended primary contact, a closure of insulation material carried by said casing, a massage implement carried by said closure, a fixed contact member carried by said closure in operative relation to said extended primary contact and in electrical connection with said casing, a second fixed contact member carried by said closure in operative relation to said series of separated contact terminals and in electrical connection with said massage implement, and means accessible from the exterior of said casing for causing a rotative movement of said member to

bring said extended primary contact into electrical engagement with said first fixed contact and one of said secondary contact terminals into electrical engagement with said second fixed contact and thereby close the primary circuit through said casing and throw said massage implement into said secondary circuit; substantially as described. 70

8. In a massage instrument, a handle in the form of a metallic casing, a member rotarily movable in said casing about the longitudinal axis thereof, an induction coil with its armature carried by and movable with said member and having a divided secondary winding, a battery arranged in, and in electrical engagement at one side with, said casing, said battery being normally at its other side in electrical connection with the primary winding of said coil and its said armature and adapted therewith to provide a source of intermittent current for the primary winding of said coil, an extended contact terminal carried by said member for the primary winding of said coil, a series of separated contact terminals for said divided secondary winding of said coil carried by said member at the same end thereof as said extended primary contact, a closure of insulation material carried by said casing, a massage implement carried by said closure, a fixed contact member carried by said closure in operative relation to said extended primary contact and in electrical connection with said casing, a second fixed contact member carried by said closure in operative relation to said series of separated contact terminals and in electrical connection with said massage implement, and means accessible from the exterior of said casing for causing a rotative movement of said member to bring said extended primary contact into electrical engagement with said first fixed contact and one of said secondary contact terminals into electrical engagement with said second fixed contact and thereby close the primary circuit through said casing and throw said massage implement into said secondary circuit; substantially as described. 105

9. In a massage instrument, a handle in the form of a metallic casing, a member including a metallic frame rotarily movable in said casing about the longitudinal axis thereof, an induction coil with its armature carried by and movable with said frame and having a divided secondary winding, a battery arranged in, and in electrical engagement at one side with, said casing, said battery being normally at its other side in electrical connection with said frame and therethrough with the primary winding of said coil and its said armature and adapted therewith to provide a source of intermittent current for the primary winding of said coil, an extended contact terminal carried by said member for the primary wind- 115

120

125

130

- ing of said coil, a series of separated contact terminals for said divided secondary winding of said coil carried by said member at the same end thereof as said extended primary contact, a closure of insulation material carried by said casing, a massage implement carried by said closure, a fixed contact member carried by said closure in operative relation to said extended primary contact and in electrical connection with said casing, a second fixed contact member carried by said closure in operative relation to said series of separated contact terminals and in electrical connection with said massage implement, and means accessible from the exterior of said casing for causing a rotative movement of said member to bring said extended primary contact into electrical engagement with said first fixed contact and one of said secondary contact terminals into electrical engagement with said second fixed contact and thereby close the primary circuit through said casing and throw said massage implement into said secondary circuit; substantially as described.
10. In a massage instrument, a casing, and a member arranged in said casing and comprising a conducting frame, an induction coil carried by said frame and having its armature normally in electrical connection therewith, said coil being provided with a divided secondary winding, an extended contact terminal carried by said member for the primary winding of said coil, and a series of separated contact terminals carried by said member for the divided secondary winding of said coil; substantially as described.
11. In a massage instrument, a casing, and a member arranged in said casing and comprising a conducting frame, a plurality of series-wound induction coils carried by said frame and having a divided secondary winding, the cores of said coils lying closely adjacent and forming with said frame a substantially horse-shoe magnet, an armature normally in electrical connection with said frame and carried thereby in operative relation to said cores, an extended contact terminal carried by said member for the primary winding of said coil, and a series of separated contact terminals carried by said member for the divided secondary winding of said coils; substantially as described.
12. In a massage instrument, a casing, and a member arranged in said casing and comprising a base, a head, a conducting frame carried by and between said base and head, a plurality of series-wound induction

coils carried by said frame and having a divided secondary winding, the cores of said coils lying closely adjacent and forming with said frame a substantially horse-shoe magnet, an armature normally in electrical connection with said frame and carried thereby in operative relation to said cores, an extended contact terminal carried by said head for the primary winding of said coil, and a series of separated contact terminals carried by said head for the divided secondary winding of said coils; substantially as described.

13. A massage instrument comprising a conductor handle, an interrupter rotatably mounted therein, a massage roller carried by one end of said handle, said interrupter provided with a plurality of disk portions, a substantially U-shaped frame between said disk portions, and secured thereto, induction coils carried by said substantially U-shaped frame, an armature carried by said substantially U-shaped frame and adapted to be attracted by said coils when the current passes therethrough, and contact means communicating with said interrupter and roller and battery for supplying an electrical current therethrough.

14. A massage instrument comprising a suitable massage implement, a handle therefor, a frame rotatably mounted in said handle, induction coils carried by said frame, a battery housed in said handle, and contact terminals formed upon said battery and frame, said coils being electrically connected with said contact terminals carried by said frame, whereby when said frame is rotated in said handle various contact terminals will be brought into contact with said coils for regulating the flow of current therethrough.

15. A massage instrument comprising a suitable massage implement, a handle therefor, a frame rotatably mounted in said handle, a battery housed in said handle, induction coils carried by said frame, means extending through said handle and engaging said frame for allowing the frame to be easily rotated, contact terminals carried by said frame, said coils being electrically connected with said contact terminals, and means co-operating therewith for regulating the flow of current therethrough.

In testimony whereof I hereunto affix my signature in presence of two witnesses.

DANIEL TIBBALS.
